APPARATUS FOR PARALLAX CORRECTION

Richard C. Knowles, New York, and Herbert Harris, Jr., Cedarhurst, N. Y., assignors to Sperry Gyroscope Company, Inc., Brooklyn, N. Y., a corporation of New York

Application March 1, 1943, Serial No. 477,666

10 Claims. (Cl. 235—61.5)

1

This invention relates, in general, to a method and apparatus for correcting gun aiming angles due to the spacing of the gun station from a control or sighting station. It is particularly directed to parallax correction in inter-aircraft fire control systems.

Increases in the size of aircraft have increased the number of gun positions carried by the craft, as well as increasing the size and range of the guns. These factors have made it desirable to obtain greater accuracy from the guns by increasing the accuracy of the fire control system. With the increase in the number of gun positions it was found desirable to have one or more central fire control stations for aiming all or any portion of the guns on the craft at selected targets.

The high velocities involved in the prediction computations necessary for inter-aircraft fire control systems have made it further desirable to correct for errors heretofore considered as insignificant. The accuracy of inter-aircraft fire control systems has reached the point where the off-set of gun stations relative to the fire control stations has become an important factor and is becoming more important as the size of aircraft increases.

Therefore, the present invention contemplates a fire control system having several gun positions, any one or more of which may be controlled by one or more central control stations.

In the past, fire control systems have been divided mainly into two groups; that is, those for use on land, and those for use aboard naval craft. In both of these systems parallax corrections have been effected. However, the corrections necessary for the high accuracy required in inter-aircraft fire control systems necessitate more accurate and comprehensive parallax corrections. Thus, the present invention includes a parallax correction in which factors heretofore considered unimportant have been included to obtain more accurate fire from the aircraft.

The development of fire control systems for use on land has included parallax correction apparatus in which the data has been corrected periodically by manual adjustment, and in some cases, in which continuous adjustments have been made for a portion of the parallax correction. Such continuous adjustments usually include the azimuth parallax correction which varies the angle of train of guns in azimuth due to the spacing between the sight or control station and the gun station. Such systems, however, neglected the elevation parallax correction,

2

because usually the range of the guns was comparatively long and the difference in the range due to the positioning of the two stations was negligible relative to the range.

Some land base fire control systems, such as those used for anti-aircraft fire, operate on a "plan prediction" system in which the computing and predicting mechanisms operate in rectangular coordinates. For such systems it is possible to effect a parallax correction by introducing three constant linear distances representing three components of the distance between the two stations and corresponding to the rectangular coordinate components used in the mechanism.

In some respects, fire control systems on naval craft are similar to those on aircraft, in that the computing mechanism must consider movements of the craft, as well as movements of a target. In most naval fire control systems a continuous adjustment is made to correct for azimuth parallax. However, this is not a particularly difficult correction because the control station, as well as each of the gun stations, is usually considered to be positioned on a reference line running longitudinally of the craft. This may be referred to as the zero azimuth line, and hence it is only necessary to compute the difference in the angle of train relative to the zero azimuth line for different points along the line.

Furthermore, naval fire control systems have only corrected for elevation parallax due to the difference in height between the guns and the sighting or control station which may be located in the super-structure of the ship. Corrections for changes in elevation due to the difference in range of a target from the control station and the gun station are usually neglected for the same reason as they are neglected on a land base fire control system, namely, that the difference in range is comparatively small with respect to the total range, and also that the elevation correction is comparatively small. Another reason for neglecting this correction is that the target is usually in the same horizontal plane as the firing craft and, therefore, the elevation angle is usually a minimum and is dependent solely upon range, whereas in inter-aircraft fire the targets may be located in different horizontal planes and the elevation angle is dependent upon the relative positions of the target and the gun, as well as upon the range of the target.

For several reasons parallax correction mechanisms for inter-aircraft fire control systems are complicated. One reason for this is that the var-

us gun turrets and sighting or control stations e not necessarily arranged on a common reference line, since it is customary to position some ms, at least, in the wings of the craft as well in the fuselage.

Another reason for the complication of the correcting mechanism is that the ranges are shorter and the elevation aiming angle of the gun is dependent upon the elevation of a target relative to the gun as well as upon the range of the target. As the difference in elevation between the target and the gun increases, the elevation angle of the gun increases with range. Therefore, it is necessary to include in the parallax correction mechanism an elevation parallax correction due to the difference in range of a target relative to a sighting or control station and relative to the gun station or turret.

One factor which simplifies inter-aircraft parallax correction as compared with some naval and land installations is that all of the guns and control stations may be considered to lie in the same plane, namely, the plane of the aircraft. Although there may be some difference in the height of these stations, this is comparatively small and may be neglected for present considerations. Thus, the parallax corrections contemplated herein are due to the distance separating a gun from a control station or sight measured in the plane of the aircraft.

One object of the invention is to provide an apparatus for parallax correction including elevation parallax correction due to the difference in range of a target from two separated stations.

Another object of the invention is to provide an apparatus for parallax correction in which the correction may be computed for any position of the various stations relative to the longitudinal axis or reference line of the craft.

A further object of the invention is to provide continuous azimuth and elevation parallax corrections to determine the aiming angle for a remotely positioned gun from azimuth, elevation, and range data of a target relative to a sighting or control station.

Further objects and advantages of the invention will become apparent from the following specification and accompanying drawings, wherein:

Fig. 1 is a plan view of an aircraft showing the relative position of sighting stations and gun turrets.

Fig. 2 is a space diagram showing the position of a target relative to one sighting station and one gun turret on the craft.

Fig. 3 is a schematic illustration of a parallax correction mechanism embodying the invention and in which some parts are in section and others are broken away for purposes of clearness.

Fig. 4 is a section taken on the line 4-4 of Fig. 3.

Fig. 5 is a schematic perspective view of another parallax correction mechanism embodying the invention.

Referring first to Fig. 1, an aircraft, designated generally at 1, is illustrated as lying in a horizontal plane. Since the plane of the craft is normally horizontal, present orientation data is measured and computed relative to this plane. The zero azimuth reference line may be considered the longitudinal axis 2 of the craft and, for purposes of the following description, will be considered as the zero line with all azimuth angles being measured clockwise from the nose of the plane, as it appears in Fig. 1. It should be under-

stood that this definition of the zero azimuth line is merely one of convenience for purposes of description of the present invention, and should not be considered in a limiting sense, as any line may be used for a zero azimuth reference.

The craft 1 includes two sighting or control stations 3 and 4 in the nose and tail of the plane, respectively, which happen to be located on the zero azimuth line. However, this again is a matter of convenience, as the gun or sighting stations may be located in the wings of the craft or elsewhere at points off-set relative to the longitudinal axis 2. If the control stations 3 and 4 are off-set, the zero azimuth line for these stations is likewise off-set so it will pass through them.

The craft shown in Fig. 1 has an upper turret 5 in the fuselage and a lower turret (not shown) which is also located in the fuselage and may be directly below the upper turret 5. A pair of wing turrets 9 and 11 are carried by the respective wings of the craft. Other gun turrets may be provided at various positions on the craft such as other portions of the wings or the tail. However, those turrets shown will suffice for a description of the parallax correction with which the present invention is concerned.

Either of the control stations 3 or 4 may control all of the guns, or the control of the guns may be divided between the two control stations.

Each of the control stations includes a computing mechanism which is supplied with orientation data from a sighting device and utilizes this data to predict the future position of a target depending upon its direction and velocity. After the prediction has been computed, the computer determines angles at which guns should be aimed to direct projectiles to the point at which they will intercept a target. This point is defined as the future position of the target. The gun aiming angles thus determined apply to a gun located at the sighting or computing station. In order to correct these angles for remotely positioned guns, the parallax method and apparatus described herein was developed.

For the fuselage turret 5, which is located on the longitudinal axis 2, the azimuth parallax correction is quite similar to that previously encountered in naval fire control systems, since the correction depends solely upon the angle that a line of sight makes with a line between the sighting and gun stations which is coincident with the longitudinal axis 2. For the wing turrets 9 and 11, the line between the control station and the guns is disposed at an angle to the longitudinal axis 2. Therefore, it is necessary to include this angle at the line connecting two stations with the longitudinal axis in azimuth parallax correction computations. For both the fuselage and wing turrets it is necessary to include the elevation parallax correction due to changes in range, as will subsequently appear.

Fig. 2 is a space diagram showing the position of a target T such as the aircraft 13. The control station or computer C and gun station or turret G, selected for this diagram, corresponds to the control station 3 and gun 11 on the aircraft 1 shown in Fig. 1. From examination of this diagram, it will be apparent that the orientation angles of the target T relative to the computer C are considerably different from the orientation angles of the target T relative to the gun turret G. The computer C and turret G are both considered to lie in the plane of the craft, that is the azimuth plane, and the computer C is further considered to be positioned on the zero

azimuth axis which, in the present case, is coincident with the longitudinal axis of the craft. The line connecting the computer C with the turret G also lies in the azimuth plane.

The distance D from the target to the computer corresponds to the slant range of the target and D' represents the slant range of the target relative to the gun turret G. The point T_A represents the projection of the target T to the azimuth plane, and the lines R and R' represent the horizontal range (the range in the azimuth plane) of the target relative to the computer C and gun turret G, respectively. The azimuth and elevation angles of the target relative to the computer C are designated A_G and E_G, respectively, since the angles with which the parallax correction mechanism is concerned are gun aiming angles for directing guns from the point C toward the predicted future position of the target.

Although Fig. 2 shows lines connecting the computer and turret with the target, these lines should be considered as lines to the future position of the target. That is, the craft 13 should be considered as the future position of the target. The gun aiming angles relative to the turret G are designated by A'_G and E'_G for azimuth and elevation, respectively.

It will be apparent from Fig. 2 that the azimuth parallax correction angle ϵ_A is equal to the difference between the azimuth angle of the target relative to the gun turret and the azimuth angle of the target relative to the computer A_G. Similarly, the elevation parallax correction ϵ_E is equal to the difference between the elevation angle of the target relative to the gun turret E'_G and the elevation of the target relative to the computer E_G. These relations may be expressed by the following equations:

$$\epsilon_A = A_G - A'_G \quad (1)$$

$$\epsilon_E = E_G - E'_G \quad (2)$$

From the trigonometric relations of these angles it may be shown that

$$\epsilon_A = \sin^{-1} \left[\frac{S \sin (\alpha - A_G)}{\sqrt{R^2 + S^2 - 2S \cdot R \cos (\alpha - A_G)}} \right] \quad (3)$$

and that

$$\epsilon_E = E_G - \tan^{-1} \left[\frac{D \sin E_G}{\sqrt{R^2 + S^2 - 2S \cdot R \cos (\alpha - A_G)}} \right] \quad (4)$$

From Fig. 2 it may be seen that

$$R = D \cos E_G \quad (5)$$

By substituting for the value of R in Equation 4, it follows that

$$\epsilon_A = \sin^{-1} \left[\frac{S \sin (\alpha - A_G)}{\sqrt{(D \cos E_G)^2 + S^2 - 2S(D \cos E_G) \cdot \cos (\alpha - A_G)}} \right] \quad (6)$$

$$\epsilon_E = E_G - \tan^{-1} \left[\frac{D \sin E_G}{\sqrt{(D \cos E_G)^2 + S^2 - 2S(D \cos E_G) \cdot \cos (\alpha - A_G)}} \right] \quad (7)$$

Equations 6 and 7 may be written as

$$\sin \epsilon_A = \frac{S \sin (\alpha - A_G)}{D \cos E_G} + \frac{S^2 \sin 2(\alpha - A_G)}{2(D \cos E_G)^2} + \dots \quad (8)$$

$$\sin \epsilon_E = \frac{S \sin E_G \cdot \cos (\alpha - A_G)}{D} + \frac{S^2 \sin E_G}{2D \cos E_G} + \dots \quad (9)$$

It has been determined empirically that all but the first expression in the series of the above equations may be eliminated, and further that the azimuth and elevation parallax corrections are sufficiently small that the angles (measured in mils) may be considered equivalent to their sines.

Thus, the azimuth and elevation parallax corrections may be approximated as

$$\epsilon_A = \frac{S \sin (\alpha - A_G)}{D \cos E_G} \quad (10)$$

and

$$\epsilon_E = \frac{S \sin E_G \cdot \cos (\alpha - A_G)}{D} \quad (11)$$

From the foregoing equations it is apparent that the azimuth parallax correction ϵ_A varies in accordance with the horizontal range R; the angle $(\alpha - A_G)$ defined by the line representing the horizontal range R and the line connecting the control station C and the gun turret G and the distance S between the control station and the gun turret. Similarly, the elevation parallax correction ϵ_E varies in accordance with the slant range D; the angle $(\alpha - A_G)$ defined by the line representing the horizontal range R and the line connecting the control station C to the gun turret G; the elevation of the target E_G; and the distance S between the two stations.

Since Equations 10 and 11 represent solutions for the desired azimuth and elevation parallax correction angles, and since these angles are expressed in terms of quantities available at the computer, it is possible to determine parallax correction angles by suitable mechanisms for solving these equations. One such mechanism which may be used to solve the equations is shown schematically in Fig. 3.

As previously stated, a computer in the fire control system determines the azimuth and elevation gun aiming angles A_G and E_G with respect to the control station C. The data thus computed is used to position shaft 21 in accordance with the gun azimuth at the computer and shaft 22 in accordance with the gun elevation at the computer. The range of the target is also determined at the computer and this data may be used to position shaft 23. It should be understood that this parallax correction mechanism is intended for use with a computer that continuously computes target orientation data and gun aiming angles. Therefore, the shafts 21, 22 and 23 will be continuously positioned in accordance with the azimuth, elevation and range calculated by the computer.

Shaft 21 rotates a pinion 24 that meshes with a gear 25 to drive the azimuth data into a differential 26. The other input of this differential 26, as represented by shaft 27, is positioned in accordance with the angle between the longitudinal 55 reference line (zero azimuth line) of the craft and

the line connecting the control station C with the gun station G, that is, the angle α . This shaft 65 is rotated an amount corresponding to the angle α by a gear 28 that is driven from a rack 29, the rack being positioned by a solenoid 31 in one of two positions, thus providing for introducing either of two separate values of α where the 70 mechanism is used for guns in different positions on the aircraft. By varying the limits of the translation of the rack 29, the values of α may be adjusted for any given installation. The inputs to the differential 26 are arranged in such a manner that the difference between the angle α and

the gun azimuth A_G will appear on the output gear 33. Thus, the gear 33 is continuously positioned in accordance with the angle $(\alpha - A_G)$ between the line representing horizontal range R and the line connecting the two stations. Rotation of gear 33 drives through gear 34, shaft 35 and bevel gears 36 and 37 to position a shaft 38 in accordance with the angle $(\alpha - A_G)$. The shaft 38 also positions a pinion 39 in accordance with this angle. Pinion 39 drives one disc 40 of a component resolving mechanism 41 that positions a slot 42 in the disc 40 in accordance with the angle $(\alpha - A_G)$. The outer disc 43 of the resolving mechanism 41 is positioned in accordance with a reciprocal of the slant range

$$\left(\frac{1}{D}\right)$$

of the target in a manner to be described.

The shaft 23 that is positioned in accordance with the slant range D drives through bevel gears 44 and 45 to rotate a shaft 46 carrying a cam 47. The surface of the cam 47 is so designed that a follower 48 riding thereon will be positioned in accordance with the reciprocal of the range

$$\left(\frac{1}{D}\right)$$

as the shaft rotates in accordance with the slant range D. This follower translates a rack 49 that meshes with a pinion 51 to drive through a shaft 52, bevel gears 53 and 54 to position an input shaft 55 of a differential 56 in accordance with the reciprocal of the range

$$\left(\frac{1}{D}\right)$$

This reciprocal of the range

$$\left(\frac{1}{D}\right)$$

is driven through the differential to the output gear 57, which positions an idler gear 58 to drive the lower disc 43 of resolving mechanism in accordance with the reciprocal of the slant range

$$\left(\frac{1}{D}\right)$$

As may be seen in Fig. 4, the lower disc 43 drives a pinion 61 that meshes with a rack 62 mounted on a block 63 that slides along guides in the slot 42 in the upper disc 40. Thus rotation of the lower disc 43 will translate the block 63 in the slot 42 and since the lower disc is rotated in accordance with the reciprocal of the slant range

$$\left(\frac{1}{D}\right)$$

this block 63 will be positioned in accordance with the same quantity.

The purpose of the differential 56 is to avoid movements of the upper disc from causing movement of the block 63 in the slot 42 which would occur due to the fact that the rack moves with the upper disc and meshes with the pinion 61, which might be held relatively stationary. The differential 56 accomplishes this by meshing input gear 65 with the upper disc 40 thereby driving the lower disc 43 an amount corresponding to all movements of the upper disc. Hence, the pinion 61 and rack 62 will rotate as a unit and only when the shaft 52 drives a change in the range into the differential 56 will the block 63 be moved relatively to the upper disc 40.

A pair of racks 71 and 72 are arranged to slide in horizontal and vertical guides (not shown), re-

5 spectively. The rack 71 carries an arm 73 that has a slot 74 formed therein and adapted to receive a pin 75 that is carried by the block 63. It will be apparent that movements of the pin 75 due to movement of either one or both of the discs 40 and 43 will cause horizontal movement of the rack 71 and arm 73.

6 Similarly, the vertical rack 72 has an arm 71 formed with a slot 78 also adapted to receive the pins 75, whereby movement of the block 63 will cause vertical movements of the rack 72.

By reference to Fig. 3, it will be seen that slot 42 is positioned by the disc 40 at an angle to the vertical equal to the angle $(\alpha - A_G)$. Since the block 63 is translated along slot 42 an amount equal to the reciprocal of the slant range

$$\left(\frac{1}{D}\right)$$

20 the racks 71 and 72 are respectively translated by amounts corresponding to the horizontal and vertical components of this reciprocal which may be expressed in terms of sine and cosine of the angle $(\alpha - A_G)$, respectively. Thus, the rack 71 is translated an amount corresponding to the expression

$$\frac{\sin(\alpha - A_G)}{D}$$

30 and the rack 72 is translated an amount corresponding to

$$\frac{\cos(\alpha - A_G)}{D}$$

35 The rack 71 meshes with a gear 81 that drives through shaft 82, bevel gears 83 and 84 to position a shaft 85 and pinion 86 in accordance with the expression

$$\frac{\sin(\alpha - A_G)}{D}$$

40 Similarly, the rack 72 drives through a pinion 145, shaft 146 and bevel gears 147 and 148 to position a shaft 149 and pinion 150 in accordance with the expression

$$\frac{\cos(\alpha - A_G)}{D}$$

45 It will be apparent that at any time these quantities may be changed for different turrets by merely causing the solenoid 31 to adjust shaft 27 in accordance with a different angle α . This will automatically adjust pinions 86 and 93 to provide the corresponding data for the different turrets.

50 The pinion 86 meshes with a rack 87 to translate a three-dimensional cam 88 that is rotated by an elongated pinion 89 on shaft 22. Thus, the cam 88 is translated in accordance with the expression

$$\frac{\sin(\alpha - A_G)}{D}$$

55 and is rotated in accordance with the gun elevation, since the shaft 22 is connected to the computer for obtaining this data. The surface of the cam 88 is laid out in a manner such that it will multiply the input from pinion 86 by the reciprocal of the cosine of the elevation angle and thus translate a follower 89 riding on the surface of the cam an amount proportional to the expression

$$\frac{\sin(\alpha - A_G)}{D \cos E_G}$$

60 Thus, the follower 89 has computed the azimuth parallax correction ϵ_A with the exception

of the multiplication by the distance S between the sighting station or computer and the gun station or turret G. This multiplication is effected in a manner now to be described.

The follower 89 carries a rack 91 that meshes with a pinion 92 on shaft 93 which drives through bevel gears 94 and 95, shaft 96 and bevel gears 97 and 98 to rotate a shaft 99 in accordance with the foregoing expression. Shaft 99 is arranged to alternatively drive through a clutch 101 or a 10 clutch 102 to rotate either pinion 103 or pinion 104. These clutches are controlled through translation of a sleeve 106 on the shaft 99 by a lever 107 pivoted at 108 that engages a collar 109 on the sleeve 106. The position of the lever 107 is adjusted by a solenoid at 111 which moves core 112 to close either clutch 101 or 102.

As shown in the drawings, clutch 101 is closed and the shaft 99 is driving through pinion 103 to drive gear 113. The ratio of the pinion 103 to gear 113 is chosen to be proportional to the distance S between the sighting station and the gun turret. Thus, the gear 113 is positioned in accordance with the expression

$$S \times \frac{\sin(\alpha - A_G)}{D \cos E_G}$$

to obtain the azimuth parallax correction angle ϵ_A in accordance with Equation 10.

When the core 112 of the solenoid 111 is in its other position, link 107 opens clutch 101 and closes clutch 102, whereby shaft 99 drives through pinion 104 to position gear 115 in accordance with the azimuth parallax angle ϵ_A for a different value of S. The gears 113 and 115 are integral and are arranged to drive the azimuth parallax correction angle into a differential 116. The other input to the differential is driven by the shaft 21. Thus, the differential 116 adds the gun azimuth A_G at the computer to the azimuth parallax correction angle ϵ_A to obtain the gun azimuth angle A'_G at a selected turret by rotating output gear 117 in accordance with that angle A'_G . Thus, output gear 117 meshes with a suitable gear 118 to drive a shaft 119 in accordance with the gun azimuth angle A'_G at the selected turret. A suitable data transmission and servo system may be controlled by the position of shaft 119 to position guns at the remote turret in azimuth corresponding to the angle A'_G .

The elongated pinion 89 also rotates a three-dimensional cam 121 in accordance with the gun elevation angle at the computer by rotating a gear 122 on the cam. The cam 121 is translated by a rack 123 that meshes with the pinion 150 whereby the cam 121 is translated in accordance with the expression

$$\frac{\cos(\alpha - A_G)}{D}$$

The surface of the cam 121 is laid out in a manner such that the expression by which the cam is translated will be multiplied by the sine of the gun elevation angle E_G and a follower 124 riding on the surface of the cam will be translated an amount corresponding to the expression

$$\frac{\sin E_G \cos(\alpha - A_G)}{D}$$

The follower 124 carries a rack 125 that meshes with a pinion 126 to drive a shaft 127 in accordance with the foregoing expression. The shaft 127 operates through clutches 128 and 129 to drive pinions 131 and 132. The clutches 128 75

and 129 are actuated by the solenoid 111 through link 133 pivoted at 134, which engages a collar 135 to alternatively open and close the two clutches in a manner similar to that described in connection with clutches 101 and 102. The ratio of pinion 131 to gear 136 is the same as the ratio of pinion 103 to gear 113, that is, a value proportional to the distance S, between any two stations. The ratio of the pinion 132 to gear 138 is proportional to a similar distance S for two other stations and is equal to the ratio of the pinion 104 to the gear 115.

The shaft 127 drives through clutch 128 to rotate gear 136 in accordance with the elevation parallax correction angle as determined by Equation 11. Gears 136 and 138 are integral and represent one input to a differential 141, the other input of which is driven by the shaft 22 in accordance with the gun elevation angle E_G at the computer. The differential 141 adds the gun elevation angle E_G at the computer and the elevation parallax correction angle ϵ_E to position output gear 142 in accordance with the gun elevation angle E'_G at the turret. The gear 142 drives a gear 143 to position shaft 144 in accordance with the gun elevation angle at the turret. Shaft 144 may be connected through suitable data transmission and servo mechanisms to position the elevation angle of the gun E'_G at the remote turret.

In the mechanism just described, provision is made for introducing two values of the angle α of the line connecting a turret and sighting station relative to the azimuth reference line. Also, provision is made for introducing two values of the distance S between a turret and sighting or control station. It should be understood that suitable mechanism for introducing more than two values of α and S may be provided without departing from the invention.

The provision for changing the values of α and S makes the use of this mechanism flexible. It is readily adaptable for use with one turret and more than one computer or with one computer and more than one turret. For example, if a parallax correction mechanism is installed for each turret, the values of α and S may be adjusted for different control stations as the control of the turret is switched from one control station to another.

For example, if a mechanism is provided for the turret 11, the values of α and S may be set in for either control station 3 or control station 4 depending upon which station was supplying data to the turret.

On the other hand, if a parallax correcting mechanism is installed for each control station, the values of α and S may be adjusted for different turrets. For example, if a mechanism 60 was installed for control station 3, the values of α and S may be adjusted for turrets 9 and 11. Furthermore, the devices for adjusting the values of α and S may be modified to provide more than two adjustments and thereby permit the computation of parallax correction between any number of stations.

It is contemplated that a mechanism similar to that shown in Fig. 3 may be used in conjunction with each of the computers or control 70 stations on an aircraft. Thus, the gun aiming angles determined by the computers at the control stations may be corrected to a suitable turret to position the gun at that turret so it will be directed toward the predicted future position of a target. This mechanism uses only the data

that is supplied by a computer, namely, the azimuth, elevation and range data of the target's future position relative to the computer.

Another mechanism for determining the azimuth and elevation parallax correction in accordance with Equations 10 and 11, respectively, is illustrated in Fig. 5 and will now be described. In this mechanism, shafts 151, 152 and 153 are positioned by the computer in accordance with the gun azimuth angle, gun elevation angle and range relative to the computer in a manner similar to that in which the shafts 21, 22 and 23 of the mechanism shown in Fig. 3 are positioned.

The shaft 152 drives through gearing 153 and shaft 154 to rotate an elongated pinion 155 in accordance with the gun elevation angle E_G at the computer. The elongated pinion 155 drives a gear 156 that is mounted on a three-dimensional cam 157 to also rotate the cam in accordance with the elevation angle E_G . Cam 157 is translated by a rack 158 that meshes with a pinion 159 on the shaft 153, whereby the cam 157 is translated in accordance with the range D of the target. The surface of cam 157 is laid out in a manner such that a follower 161 riding thereon is translated in accordance with expression

$$D \cos E_G$$

A second three-dimensional cam 163 is integral with the cam 157, whereby it also is rotated in accordance with the gun elevation E_G and translated in accordance with range D . The surface of the cam 163 is laid out in a manner such that follower 164, riding thereon, will be positioned in accordance with the expression

$$\frac{\sin E_G}{D}$$

Three identical three-dimensional cams 165, 166 and 167 are mounted on the follower 161 and are translated thereby in accordance with the expression

$$D \cos E_G$$

Additional cams may be mounted on the follower 161 to provide for correcting the data supplied to more turrets, as will subsequently become apparent. These three cams 165, 166 and 167 are rotated in accordance with the gun azimuth angle A_G at the computer by an elongated pinion 169. The elongated pinion 169 is rotated in accordance with A_G by shaft 151 which is connected thereto through suitable gearing 171, 172, 173 and 174, including shafts 175, 176 and 177.

When the mechanism is assembled, each of the cams is set with respect to the pinion 169 and the other cams in accordance with the angle α for its particular turret, that is, the azimuth angle between the zero azimuth line and the line connecting the computing or sighting station and the gun turret or station. By setting the three cams at different angles α with respect to pinion 169, provision is made for transmitting data simultaneously to three turrets arranged in different positions relative to the computing or sighting stations. Assuming the pinion 169 is arranged at zero azimuth, each of the cams 165, 166 and 167 will be adjusted angularly by an amount corresponding to the angle α for their three respective turrets. Thus, by properly selecting the direction of rotation of the pinion 169, the value of the gun azimuth angle A_G may be subtracted from the value of the angle α at which the cams are set, thus obtaining the difference between these two angles, which difference angle is the one desired to be used.

The cams 165, 166 and 167 are translated in accordance with the expression

$$D \cos E_G$$

and are rotated in accordance with the difference angle $(\alpha - A_G)$. The surfaces of these cams are such that followers 181, 182 and 183, riding thereon, are translated in accordance with the expression

10

$$\frac{\sin (\alpha - A_G)}{D \cos E_G}$$

The only differences in the translation of these three followers will be the difference in the angle α for the three turrets, that is, the difference in the angle α by which the three cams 165, 166 and 167 are originally set.

Follower 181 carries a rack 185 that meshes with a pinion 186 that rotates a shaft 187 to drive gears 188 and 189. The ratio of the gears 188 and 189 is proportional to the distance S between the computing station and the same gun turret for which the cam 165 was originally positioned by the angle α . Since shaft 187 is positioned in accordance with the expression

25

$$\frac{\sin (\alpha - A_G)}{D \cos E_G}$$

the shaft 191 will be positioned by a similar quantity but multiplied by the distance S between the computing and gun station. Thus, the shaft 191 will be positioned in accordance with the azimuth parallax correction angle ϵ_A , as determined by Equation 10.

30 The shaft 191 drives this value of the azimuth parallax correction angle ϵ_A into a differential 192. The other input of differential is driven in accordance with the gun azimuth angle A_G at the computer by gearing 193 from the shaft 175, which thereby drives shaft 194, gear 195 and the other input gear 196 into the differential 192.

35 Output gear 197 of the differential 192 is thus positioned in accordance with the sum of the gun azimuth angle A_G at the computing station and the azimuth parallax correction angle, ϵ_A , which sum is equivalent to the gun azimuth angle A'_G at the particular gun turret for which the values of α and S were selected. This gun azimuth angle A'_G may be transmitted to the remote turret through suitable data transmission and servo systems. Such systems may be controlled by azimuth transmitter 198, which is positioned in accordance with the gun azimuth at the selected turret by gear 197 which meshes with a gear 199 to position the rotor or the transmitter 198 as by shaft 201.

40 The addition of the azimuth parallax correction angle and the gun azimuth angle may be accomplished in any well known manner. The use of a differential for this purpose is merely illustrative of any suitable summing device. For example, the shaft 191, which is rotated in accordance with the parallax correction angle ϵ_A , might be utilized to rotate the casing of the transmitter 198 and have the gun azimuth angle shaft 175 drive the rotor of the transmitter 198. Thus, the output of the transmitter would represent the sum $(A_G + \epsilon_A)$ which would be the corrected gun aiming angle A'_G .

45 For a second turret, the follower 182 drives pinion 203 and shaft 204 to rotate gears 205 and 206, whereby the quantity determined by the follower 182 is multiplied by the value of S for the second turret. This product is driven 50 by shaft 207 to a differential 208, the other input

of which is driven in accordance with the gun azimuth A_g at the computer in the same manner as that described with respect to differential 192. Thus, output gear 209 of the differential 208 is positioned in accordance with the gun azimuth angle A'_g at the second turret and drives through gear 211 and shaft 212 to position the rotor of a transmitter 213 which controls suitable transmission and servo systems for positioning the gun in the second turret.

Similarly, the product of the quantity represented by the follower 183 and the quantity S for the third turret, are multiplied by gears 215 and 216 which drive shaft 217 in accordance with the azimuth parallax correction angle α for the third turret. The shaft 217 drives the correction angle into a differential 218, the other input of which is positioned in accordance with the gun azimuth A_g at the computer by the shaft 175. Thus, output gear 219 drives through gear 221 and shaft 223 to position the rotor of a transmitter 224 in accordance with the gun azimuth angle A'_g for the third turret.

As previously described, the follower 164 on the cam 163 is positioned in accordance with the expression

$$\frac{\sin E_g}{D}$$

This follower 164 translates three cams 225, 226 and 227 in accordance with this expression. These cams are rotated an amount corresponding to the difference angle $(\alpha - A_g)$ in the same manner as that described in connection with cams 165, 166 and 167, the angle α being adjusted for the three different turrets in accordance with the original position of the cams with respect to the elongated pinion 169. Additional cams for additional turrets may also be translated by the follower 164. The three cams 225, 226, and 227 are rotated in accordance with the difference angle by gears 228, 229 and 231 mounted on the three cams, respectively, which mesh with the elongated pinion 169. The cams 225, 226 and 227 are laid out in a manner such that followers 233, 234 and 235 riding on their respective surfaces will be positioned in accordance with the expression

$$\frac{\sin E_g \cos (\alpha - A_g)}{D}$$

the value of α being different for each of the three cams.

This expression is multiplied by the corresponding value of S for each of the three turrets and by the ratio of gears 241 to 242; 243 to 244; and 245 to 246. A rack 247 on the follower 243 meshes with a pinion 248 which drives through shaft 249 to position the gear 241. Similarly, racks 251 and 252 on followers 234 and 235, respectively, mesh with pinions 253 and 254 to drive shafts 255 and 256 which in turn are connected to pinions 243 and 245. It will be apparent that shafts 257, 258 and 259 will be positioned in accordance with the elevation parallax correction angle ϵ_E , as determined by Equation 11 since each of the shafts 249, 255 and 256 has been multiplied by a quantity corresponding to the distance S between the computer and the three respective turrets.

The elevation parallax correction angle ϵ_E for the first turret is driven into the input of the differential 261, the other input of which is driven by shaft 152, gearing 263, shaft 264, gearing 265, and gearing 266 to drive the gun elevation angle

75

E_g at the computer into the differential 261. The output of the differential 261 represents the sum of the gun elevation angle E_g at the computer, and the elevation parallax correction angle ϵ_E , which sum is equal to the gun elevation angle E'_g at the turret. This output acts through gearing 271 and shaft 272 to position the rotor of a suitable transmitter 273 for controlling data transmission and servo systems to aim the gun in the first turret in accordance with the gun elevation angle E'_g therefor.

In a similar manner, differential 275 is driven by shaft 258 in accordance with the elevation parallax correction angle ϵ_E for the second turret, and by a shaft 277 in accordance with the gun elevation angle E_g at the computer. This differential 275 adds these two angles to obtain the gun elevation angle E'_g at the second turret and positions the rotor of a suitable transmitter 274 as by gearing 279 and gearing 281 and shaft 282 in accordance with said gun elevation angle at the second turret. Similarly, shaft 259 and a shaft 284 drive the elevation parallax correction angle ϵ_E for the third turret and the gun elevation angle E_g at the computer into a differential 285, the output gear 286 of which is positioned in accordance with the gun elevation angle E'_g at the third gun turret. The gear 286 drives through a gear 288 and shaft 289 to position the rotor of a suitable transmitter 291 for actuating suitable transmission and servo systems to control the elevation angle of the gun in the third turret.

The parallax correction mechanism described in connection with Fig. 3 provides a simple mechanism for determining the parallax correction angle of a selected turret. The mechanism may be adjusted by adjusting the values of S and α for this turret. The parallax correction mechanism described in connection with Fig. 5 provides continuous correction data simultaneously for several turrets. The mechanism illustrated in Fig. 5 corrects the computer data for three different turret positions. As has been previously stated, additional cams may be translated by followers 161 and 164. Thus, by providing such additional cams and their auxiliary equipment, the computer data may be corrected for as many turrets as desired. It will be apparent that this mechanism is readily adjustable for different crafts by merely adjusting the relative positions of the cams in accordance with the angle α for the various turrets, and by adjusting the gear ratios in accordance with the various values of S .

For those turrets located on the longitudinal reference line of the craft, the mechanisms are operated in the same manner as for turrets located in the wings. However, the angle α relative to the zero azimuth line becomes 0° or 180° . Thus, the mechanism is adjustable for all conditions and corrections for additional turrets may be added to the mechanism as required.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

70 What is claimed is:

1. In a parallax correction mechanism, means for computing the azimuth parallax correction angle comprising an element for introducing the azimuth angle of a line of aim from one station to a point measured relative to a zero azimuth

reference line through said one station, an element for introducing the elevation angle of said line of aim relative to a reference plane including said zero azimuth line, an element for introducing the range of said point relative to said one station, a device set according to the azimuth angle between said zero reference line and a base line from said one station to a remote station and actuated by said first element for determining the angular difference between the azimuth angle of said base line and said azimuth angle of the line of aim to said point, and a mechanism responsive to said elements and said device for computing the azimuth parallax correction angle for said remote station.

2. In a parallax correction mechanism, means for computing the azimuth parallax correction angle comprising an element for introducing the azimuth angle of a line of aim from one station to a point measured relative to a zero azimuth reference line through said one station, an element for introducing the elevation angle of said line of aim relative to a reference plane including said zero azimuth line, an element for introducing the range of said point relative to said one station, a device set according to the azimuth angle between said zero reference line and a base line from said one station to a remote station and actuated by said first element for determining the angular difference between the azimuth angle of said base line and said azimuth angle of the line of aim to said point, a device actuated by said second and third elements for computing the azimuth projection of the range of said point, and a mechanism actuated by said devices for computing the azimuth parallax correction angle of said point for said remote station.

3. A parallax correction mechanism comprising means for computing the elevation parallax correction angle, said means including an element for introducing the azimuth angle of a line of aim from one station to a point measured relative to a zero azimuth reference line through said one station, an element for introducing the elevation angle of said line of aim relative to a reference plane including said zero azimuth line, an element for introducing the range of said point relative to said one station, a device set according to the azimuth angle between said zero reference line and a base line from said one station to a remote station and actuated by said first element for determining the angular difference between the azimuth angle of said base line and said azimuth angle of the line of aim to said point, and a mechanism actuated by said elements and said device for computing the elevation parallax correction angles for said remote station.

4. An azimuth parallax correction mechanism comprising a first device actuated according to the range of a point relative to a first station and the elevation angle of a line of aim from said first station to said point measured relative to a reference plane including said first station for providing a measure of the product of said range and a cosine function of said elevation angle, a second device actuated by said first device and according to the angular difference between the azimuth angle of the line of aim measured relative to a zero azimuth reference line in said reference plane and the azimuth angle of a base line joining said first station and a remote station also measured relative to said zero reference line for providing a measure

of the quotient of a sine function of said difference angle divided by said product, and mechanism actuated by said second device for multiplying said quotient by the distance between said stations for computing the azimuth parallax correction angle corresponding to the difference between said azimuth angle of the line of aim from said point to said first station and the azimuth angle of a line from said point to said remote station.

5. An elevation parallax correction mechanism comprising a first device actuated according to the range of a point relative to a first station and the elevation angle of a line of aim from said first station to said point measured relative to a reference plane including said first station for providing a measure of the quotient of a sine function of said elevation angle divided by said range, a second device actuated by said first device and according to the angular difference between the azimuth angle of the line of aim measured relative to a zero azimuth reference line in said reference plane and the azimuth angle of a base line joining said first station and a remote station for providing a measure of the product of a cosine function of said difference angle multiplied by said quotient, and mechanism actuated by said second device for multiplying said product by the distances between said stations to compute the elevation parallax correction angle corresponding to the difference between the said elevation angle of the line of aim from said point to said first station and the elevation angle of a line from said point to said remote station.

6. A parallax correction mechanism comprising a range member settable according to the range of a point relative to a first station, an elevation member settable according to the elevation angle of a line of aim from said first station to said point measured relative to a reference plane including said first station, a first device actuated by said members for providing a measure of the product of said range and a cosine function of said elevation angle, a second device actuated by said members for providing a measure of the quotient of a sine function of said angle divided by said range, an azimuth member settable according to the azimuth angular position of said line of aim measured relative to a zero reference line including said first station, a third device actuated by said first device and said azimuth member according to the angular difference between the azimuth angle of the line between said first station and the said remote station measured relative to said zero reference line and said azimuth angle of said line of aim for providing a measure of the quotient of a sine function of said difference angle divided by said product, mechanism actuated by said third device for multiplying said quotient by the distance between said stations to compute the azimuth parallax correction angle of said point with respect to said stations, a fourth device actuated by said second device and said azimuth member according to said difference angle for providing a measure of the product of said quotient multiplied by a cosine function of said difference angle, and mechanism actuated by said fourth device for multiplying said product by the distance between said stations to compute the elevation parallax correction angle of said point with respect to said two stations.

7. An azimuth parallax correction mechanism comprising an azimuth element for providing a

measure of the azimuth angular position of a line of aim from a point to a first station measured relative to a zero azimuth reference line including said first station, an elevation element for providing a measure of the elevation angle of said line of aim measured relative to a reference plane including said reference line, a range element for providing a measure of the range of said point with respect to said first station, computing means actuated by said three elements for computing the quotient of a sine function of said azimuth angle divided by the product of a cosine function of said elevation angle and the range of said point, gear means driven by the output of the computing means having a predetermined ratio proportional to the distance between said first and a second station for multiplying said quotient by said distance to provide a measure of the azimuth parallax correction angle between said stations, and a clutch controlling the gear means operable to change said gear ratio to a different predetermined ratio proportional to the distance between said first station and a third station, to adapt the mechanism at will for use with the latter station and said first station.

8. An elevation parallax correction mechanism comprising an azimuth element for providing a measure of the azimuth angular position of a line of aim from a point to a first station measured relative to a zero azimuth reference line including said first station, an elevation element providing a measure of the elevation angle of said line of aim measured relative to a reference plane including said reference line, a range element for providing a measure of the range of said point with respect to said first station, computing means actuated by said three elements for computing the product of the sine of said elevation angle and the cosine of said azimuth angle divided by the range of said point, gear means driven from the output of the computing means having a ratio proportional to the distance between said first and a second station for multiplying said output by said distance to provide a measure of the elevation parallax correction between said stations, a clutch controlling the gear means operable to change said gear ratio to a different predetermined gear ratio proportional to the distance between said first station and a third station, whereby the mechanism may be adapted by the operation of the clutch for use with the latter station and said first station.

9. An azimuth parallax correction mechanism comprising an azimuth element for providing a measure of the difference angle between the azi-

imuth angular position of a line of aim from a point to a first station measured relative to a zero reference line including said first station and the azimuth angular position of a line joining said first station and a second station measured relative to said zero reference line, an elevation element providing a measure of the elevation angle of said line of aim measured relative to a reference plane including said reference line, a range element for providing a measure of the range of said point with respect to said first station, computing means actuated by said three elements for computing the quotient of a sine function of said difference angle divided by the product of a cosine function of said elevation angle and the range of said point, a member settable according to the distance between said stations, and multiplying means actuated by said computing means and said member for multiplying said quotient by said distance to provide a measure of the azimuth parallax correction angle between said stations.

10. An elevation parallax correction mechanism comprising an azimuth element for providing a measure of the difference angle between the azimuth angular position of a line of aim from a point to a first station measured relative to a zero reference line including said first station and the azimuth angular position of a line joining said first station and a second station measured relative to said zero reference line, an elevation element providing a measure of the elevation angle of said line of aim measured relative to a reference plane including said reference line, a range element for providing a measure of the range of said point with respect to said first station, computing means actuated by said three elements for computing the product of a cosine function of said difference angle multiplied by a sine function of said elevation angle, divided by the range of said point, a member settable according to the distance between said stations and multiplying means actuated by said computing means and said member for multiplying said product by said distance to provide a measure of the elevation parallax correction angle between said stations.
